(57) **CLAIM**

The ornamental design for a travel bag, as shown and described.

DESCRIPTION

FIG. 1 is a perspective view of a travel bag showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dash-dash broken lines in the drawings depict portions of the travel bag that form no part of the claimed design. The short thick evenly spaced broken lines in the drawings depict stitching and form no part of the claimed design.

1 Claim, 8 Drawing Sheets
